UNITED STATES PATENT OFFICE

RALPH N. ELLIS, OF DES MOINES, IOWA, ASSIGNOR OF ONE-HALF TO THOMAS WATTERS, JR., AND ROBERT W. COLFLESH, OF DES MOINES, IOWA

COLLAPSIBLE-TUBE TOP

Application filed April 4, 1928. Serial No. 267,446.

The object of my invention is to provide a collapsible tube top of simple, durable and comparatively inexpensive construction.

A further object of my invention is to provide a top for collapsible tubes such as those used for holding tooth paste, shaving cream or the like in which a valve seat and valve plug is arranged for cutting off the contents of the tube after a sufficient amount has been discharged.

Still a further object is to provide a tongue and cam means for moving the valve plug to either opened or closed position as desired.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of a collapsible tube embodying my improved type of top thereon.

Figure 2 is an enlarged plan view of the same.

Figure 3 is a side elevation of the top portion of the tube shown in Figure 1 and looking in the direction of the arrow 3 adjacent the top thereof.

Figure 4 is a sectional view on the line 4—4 of Figure 3, illustrating the parts of the top in closed position.

Figure 5 is a similar sectional view illustrating the parts in opened position; and

Figure 6 illustrates the use of the tube as when discharging the contents onto the tooth brush.

In the accompanying drawings, I have used the reference numeral 10 to indicate a collapsible tube. The tube 10 is formed with a top member 12 having an upwardly extending boss like portion 14. A valve seat 16 is formed in the under surface of the boss 14 and an opening 18 extends vertically through the boss.

A valve plug 20 is positioned inside the tube 10 and adapted to coact with the valve seat 16. The plug 20 is secured to a pin 22 extending through the opening 18. A tongue 24 is secured to the pin 22 and has a down-

wardly extending portion 26. A shoulder 28 is formed on the boss 14 and a pair of cam surfaces 30 are formed adjacent the top of the boss.

The portion 26 of the tongue 24 normally rests on one of the cam surfaces 30. An opening 32 is formed in the boss 14 for receiving the contents 34 from the tube 10 and discharging it as indicated at 36. The opening 32 is transversely elongated on the inside of the tube 10 and is vertically elongated on the outside of the boss 14 as shown in full and dotted lines in Figure 3 so that the contents of the tube will be discharged in ribbon like form.

In the operation of my device, the portion 26 of the tongue 24 is normally resting against one of the cam surfaces 30 for holding the valve plug 20 in closed position. By rotating the tongue 24 in the direction of the arrow 38, the portion 26 rests on the shoulder 28 for spacing the plug 20 from the seat 16 as shown in Figure 5. When the tube is then collapsed for discharging the contents 34 thereof, the plug 20 will be carried in the direction of the arrow 40 so that a predetermined amount of the contents will be discharged and the valve will then be closed.

When the member 24 is rotated it causes the cam surfaces of the adjacent parts to tightly engage each other and thus serve as a seal and lock.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A top for tubes or the like of the character described comprising a top member, a boss formed thereon, a pin slidably and rotatably mounted in said boss, a valve seat on the inner side of said boss, a valve plug on said pin to coact with said valve seat, a tongue secured to the outer end of said pin and a cam surface on said boss to coact with said

tongue, said cam surface having a depressed part.

2. A top for tubes or the like of the character described comprising a top member, a boss formed thereon, a pin slidably and rotatably mounted in said boss, a valve seat on the inner side of said boss, a valve plug on said pin to coat with said valve seat, said valve plug being capable of assuming a position spaced from said valve seat or a second position coacting therewith upon discharge of the contents of the tube and cam means adapted to coat with the pin upon rotation thereof for allowing said valve plug to assume the first position and for maintaining it in the second position.

3. A collapsible tube top comprising a top member having a valve seat and a valve plug capable of movement toward or from said seat whereby the valve plug may be caused to assume a position spaced from said valve seat or may be moved to a position coacting with the valve seat upon a discharge of the contents of the tube and manually operated means for causing the valve plug to be retained in either of said positions, said means including a tongue, a pin extending through said top member, and having its ends connected with said valve plug and with said tongue, and a cam surface adapted for coaction with said tongue.

Des Moines, Iowa, March 26, 1928.
RALPH N. ELLIS.
